DESIGN FOR A CLIP FOR SANITARY GARMENTS

Joseph D. Farkas, New Rochelle, N. Y.

Application September 15, 1938, Serial No. 79,922

Term of patent 3½ years

To all whom it may concern:

Be it known that I, Joseph D. Farkas, a citizen of the United States and resident of New Rochelle, in the county of Westchester and State of New York, have invented a new, original, and ornamental Design for a Clip for Sanitary Garments, of which the following is a specification, reference being had to the accompanying drawing, forming a part thereof, and of which Figure 1 is a view in front elevation of a clip for sanitary garments showing my new design, Fig. 2 is a view in elevation of one end of the clip, Fig. 3 is a view in elevation of the opposite end thereof, and Fig. 4 is a sectional view thereof on the line 4—4 of Fig. 1.

I claim:

The ornamental design for a clip for sanitary garments, substantially as shown.

JOSEPH D. FARKAS.
